Patented September 8, 1903.

UNITED STATES PATENT OFFICE.

AUGUST BLONDE, OF ALLEGHENY, PENNSYLVANIA.

DESIGN FOR AN ALPHABET.

SPECIFICATION forming part of Design No. 36,549, dated September 8, 1903.

Application filed July 10, 1903. Serial No. 165,034. Term of patent 7 years.

To all whom it may concern:

Be it known that I, AUGUST BLONDE, a citizen of the United States of America, residing at Allegheny, in the county of Allegheny and 5 State of Pennsylvania, have invented a new, original, and ornamental Design for an Alphabet, of which the following is a specification, reference being had therein to the accompanying drawing.

o The drawing illustrates my new and original design for an alphabet.

I claim—
The ornamental design for an alphabet.
In testimony whereof I affix my signature in the presence of two witnesses.

AUGUST BLONDE.
